MULTIPLE-JAW HAND PLIER

George Lumpkin Kennington, Jr.,
Port St. Joe, Fla.

Application November 14, 1959, Serial No. 195,592

1 Claim. (Cl. 81—47)

1 This invention relates to improvements in pliers of the reversible jaw type.

A primary object of this invention is to provide an improved pliers involving two pairs of work-engaging jaws, and novel handle structure adapted to selectively cooperate with each pair of jaws.

A still further object of this invention is to provide a multiple-jaw pliers which embodies a minimum number of parts adapted to cooperate with each other in a highly efficient manner.

A still further object of this invention is to provide a multiple-jaw pliers which is relatively simple in structure and cheap to manufacture.

The above and still further objects and advantages of the present invention will become apparent upon consideration of the following detailed description of the invention when taken in conjunction with the accompanying drawings, wherein:

Figure 1 is a top plan view of a reversible jaw pliers of the present invention;

Figure 2 is a side elevational view;

Figure 3 is an enlarged sectional view taken along the line 3—3 of Figure 1; and

Figure 4 is an enlarged fragmentary detail view taken along the line 4—4 of Figure 3.

Referring now more particularly to the drawings, wherein like reference numerals have been used throughout the several views to designate like parts, there is shown a multiple-jaw hand plier constructed according to the present invention, designated by the reference numeral 10, which includes a pair of body members 11 and 12 disposed in criss-cross relation with respect to each other and pivotally connected together intermediate their ends.

One pair of adjacent ends of the body members 11 and 12 include cooperating jaws 13 and 14 of a particular work-engaging feature. As clearly illustrated in Figure 1, the jaws 13 and 14 are of the type including opposed shears 15 and 16, the shears cooperating with each other for forming a desired work operation upon movement of the jaws 13 and 14 toward each other. The other pair of adjacent ends of the body members 11 and 12 include cooperating jaws 17 and 18 of a different work-engaging feature, the jaws 17 and 18 being illustrated as conventional long nose jaw parts. The jaw structures 13 and 14 and 17 and 18 disclosed herein are exemplary of a very great range of plier faces or jaws which are within the scope of this invention.

Arranged contiguous to one face of the pair

5 of body members 11 and 12 is a first handle 19 which is mounted for swinging movement from a position confronting the jaw 18 of the body member 11 to a position confronting the adjacent jaw 14 of the body member 12.

10 Arranged contiguous to the opposite face of the pair of body members 11 and 12 is a second handle 20 which is mounted for swinging movement from a position confronting the jaw 17 of the body member 12 to a position confronting the jaw 13 of the jaw member 11. As clearly shown in the drawings, a single headed pivot pin 21 serves as the pivotal connection for and traverses both intermediate points of the jaw members 11 and 12 and the inner ends of the handles 19 and 20.

15 Suitable fixed abutment means are carried by each of the handles 19 and 20 for engaging either the jaws 17 and 18 and the jaws 13 and 14 for moving the respective jaws toward each other in response to the movement of the handles toward each other. As clearly illustrated in Figure 20, the handle 19 carries an abutment lug 22 which is spaced outwardly from the pivot pin 21 and projects from the side thereof adjacent to and facing the handle 20, and which is arranged to engage the outer side of the jaw 18 when the handle 19 is in the position illustrated in full lines in Figure 1, the lug 22 being arranged to engage the outer side of the jaw 14 when the handle 19 is in the dotted line position illustrated in Figure 1. As shown in Figure 3, a similar abutment lug 23 carried by the handle 20 is arranged thereon to engage the outer side of the jaw 17, when the handle 20 is in the full line position shown in Figure 1, and to engage the outer side of the jaw 13 when in the dotted line position shown in Figure 1.

25 Suitable means are carried by the facing sides 40 of the handles 19 and 20 and selectively engageable with means provided on the adjacent faces of the jaws 17 and 18 and the jaws 13 and 14 for releasably securing the handles to the jaws for moving the selected jaws away from each other 30 in response to the movement of the handles 19 and 20 away from each other. As clearly illustrated in Figure 3, the handles 19 and 20 are provided with sockets 24 and 25, respectively, opening through their facing or inner sides. Detent balls 26 and 27 positioned in the sockets are biased outwardly of the facing sides of the handles 19 and 20, respectively, by means of springs 28 and 29, respectively. The outer sides of the jaws 17 and 18 are provided with depressions or 35 seats 30 and 31 for receiving the detent balls

55

26 and 27 of the handles 19 and 20. Similarly, the outer sides of the jaws 13 and 14 are provided with the depressions or seats 30 and 31 for receiving the detent balls 26 and 27.

Suitable means are formed intermediate the ends of the jaw members 11 and 12 for limiting opening movement of the respective pairs of jaws 17 and 18 and 13 and 14 away from each other. For this purpose, as clearly illustrated in Figure 1, the jaw member 11 is provided with the shoulders 35 and 36 which are arranged to cooperate with the shoulders 37 and 38 formed on the jaw member 12.

In Figure 1, the handles 19 and 20 are in position for utilization of the jaws 13 and 14 having the opposed shear surfaces 15 and 16. The jaws 13 and 14 are adapted to be moved toward and away from each other by merely moving the handles toward and away from each other. Upon effecting the movement of the handles 19 and 20 to a position wherein the shoulders 35 and 37 and 36 and 38 abut, further movement of the handles 19 and 20 away from each other will cause the detent balls 26 and 27 to disengage from the depressions or seats 30 and 31 of the jaws 17 and 18. The handles 19 and 20 can then be swung to the reversed positions illustrated by dotted lines in Figure 1, wherein the device is in position for the utilization of the long nose plier type jaws 17 and 18.

Although only one embodiment of the present invention has been shown and described herein, it is readily apparent that numerous modifications can be made without departing from the spirit of the invention as defined by the appended claim.

What I claim is:

In pliers, a pair of crossed and pivoted jaw members, said jaw members having differing jaws on their opposite ends, the jaws on the same ends of the jaw members being arranged to cooperate when the jaw members are pivoted relative to each other in directions to move the jaws at the same ends of the jaw members together, a pair of handles overlying the outer sides of

the jaw members, said handles having inner ends located at points intermediate the ends of said jaw members, a single pivot pin traversing intermediate points of said jaw members and the said inner ends of the handles, said jaw members being rotatable on the pivot pin relative to the handles for reversing the jaw members relative to the handles, means acting between the jaw members limiting opening pivotal movement of the jaw members relative to each other, and abutment lugs projecting from the facing sides of said handles, said abutment lugs being spaced along the handles from the said inner ends of the handles to abut portions of the outer edges of related jaws located intermediate the ends of the related jaws as the handles are moved toward each other from open positions and relative to the jaw members so as to pivot the jaw members relative to each other in a direction to close the other jaws, and spring biased detent means having cooperating components on the outer sides of said jaws intermediate the ends of said jaws and on the facing sides of the handles at points between the inner ends of the handles and said abutment lugs for releasably connecting the handles to the jaw members for pivoting the jaw members relative to each other in the opposite direction so as to open said other jaws.

30 GEORGE LUMPKIN KENNINGTON, JR.
